UNITED STATES PATENT OFFICE.

JOHN GERY, OF PATERSON, NEW JERSEY.

BURIAL-OVERBOX.

1,310,987.

Specification of Letters Patent. Patented July 22, 1919.

Application filed April 21, 1919. Serial No. 291,559.

To all whom it may concern:

Be it known that I, JOHN GERY, a citizen of the United States, residing at Paterson, in the county of Passaic and State of New Jersey, have invented certain new and useful Improvements in Burial-Overboxes, of which the following is a specification.

In an application for U. S. Letters Patent Serial No. 267,934 I have described and shown a burial overbox constructed with a metallic frame and a covering or shell on the frame composed of slabs of lithoidal sheet material suitably secured to the frame and having hermetically sealed joints, the whole being designed so that the parts can be stored unassembled until the overbox is required and then quickly assembled, and when assembled will form a structure which, while exceedingly light and so adapted to be taken to the grave and then lowered thereto with the casket contained therein at the time of burial, will have all the qualities to preserve its contents that characterize the best vaults built underground of man's materials. The object of this invention is to improve the construction of such overboxes so as to make them stronger in proportion to their weight; to this end I have improved the general construction of the frame and at the same time so constructed and arranged the parts forming the cover or lid that not only is the same exceedingly light and strong and well adapted to withstand the great weight of earth superimposed upon it when the grave is filled in but it very considerably reinforces and strengthens the frame in the body portion of the box itself. I have further constructed the body portion and lid of the box and the lid so as to facilitate quick and facile assembling of the lid with said body portion.

In the drawings,

Figure 1 is a perspective view of the improved overbox, portions of slabs forming the shell thereof being broken away;

Fig. 2 is a fragmentary side elevation of the frame of the body portion of the overbox.

Fig. 3 is a sectional view on the line 3—3, Fig. 2;

Fig. 4 is a plan of one corner of the frame of the body portion;

Fig. 5 is a side elevation of the frame of the body portion;

Fig. 6 is a section of the overbox, complete, on the line 6—6, Fig. 5; and

Fig. 7 is a plan of a fragment of the cover before the lithoidal slab thereof has been applied.

The body portion of the overbox is constructed as follows: Referring first to the frame thereof, *a* designates a pair of endless end frames each composed of a strip of angle iron having one wall thereof mitered out at suitable points and then bent at these points, as at *b b b b*, into substantially the shape of a rectangle (excepting that the side of the rectangle which is to form the top thereof is suitably arched as shown in Fig. 3), the ends of the strip forming a butt-joint and being secured together by a strip *c* lapping the joint and riveted to the ends of said strip *a*. To give needed stability to each of these end frames cross strips *e* connecting diagonal corner portions of the frame are riveted thereto and together where they cross each other, and one of these cross strips may be an angle strip as shown. The two end frames are connected at their bottom corners by a pair of angle strips *d* riveted thereto and arranged so as to receive the corners of the end frames in their angles; a pair of similar angle strips *f* connect and are riveted to the upper corners of the end frames *a*, receiving said corners in their angles, but in the case of these angle strips their top or horizontal flanges or walls *f'* (Fig. 5) are formed somewhat thicker than their vertical wall portions. To provide horizontal connections from one angle strip *d* to the other between the end frames *a* there is one or more (preferably two) channel strips *g*, which are riveted at their ends to the horizontal flanges of the angle strips *d*; these channel strips are adapted to rest between their ends on several plain or flat strips *h* which extend longitudinally of the frame and are riveted to said channel strips and the end frames, the channel strips being designed to afford a rest for the casket and permit the straps whereby the casket is lowered into the overbox to have the necessary clearance in withdrawing them after the casket has been deposited. To provide vertical connections from each angle strip *d* to the corresponding angle strip *f* I preferably employ a center T-iron strip *i* which is riveted at its ends to the said angle strips, and between such strip *i* and each end frame *a* an angle strip *j*, also riveted at its ends to the angle strips *d, f*. I provide as a further bracing means

for each side of the frame, essentially including the end frames *a* and the strips *d f* or their equivalent, the oblique plain or flat strips *h*, each of which preferably extends 5 from the upper corner of one end frame to the lower end of the T-iron strip *i* and is riveted to the end frame and strip *i* and also to the strip *j* where it crosses the same. The frame thus constructed is exceedingly light 10 and yet it is well adapted to support a considerable load, as the weight of the earth superimposed on the overbox when it has been deposited in the grave and the latter filled in. In further reference to the frame 15 I remark the recesses *l* which are formed at opposite points in the two angle strips *f*, to wit, in their horizontal flanges, partway of the depth thereof.

Referring to the shell of the overbox, 20 lithoidal slabs, such as a composition of cement and asbestos, *m* are employed to form the same, one such slab being secured to the bottom, each side and each end of the frame by screws *n*. The end and side 25 edges of the bottom slab *m* squarely abut the inner surfaces of the end and side slabs *m*, the top edges of the side and end slabs being all flush, and those of the end slabs being arched to conform with the tops of 30 the end frames *a*. Where any slab is opposed by another surface formed by the edge of another slab and the outer face of one of the parts *a, d, f* of the frame the joint is preferably sealed by a good moisture-resisting plastic substance, such as cement 35 (not shown).

The top or lid is constructed as follows: There are several plain or flat transverse strips *o* which have angular upstanding 40 hangers *p* formed by bending upwardly and outwardly their end portions and adapted to register with and seat in the recesses *l*. A wooden batten *q*, standing edgewise, is secured on each strip *o*, reaching from one 45 hanger *p* thereof to the other and abutting the same inwardly thereof, its top edge being arched so as to be parallel with, though somewhat below, the arched top surface of each end frame *a*. Superimposed and secured on the several battens *q* and fitting the space between the hangers *p* of the strips *o* is wooden planking *r*; the top surface of 50 this planking, when the cover is in position, will be flush with the top surfaces of the end frames *a* and the upper edges of the side and end slabs *m*. Superimposed on the planking is a lithoidal slab *s* which is arched to conform to the arched tops of the end frames *a* and preferably projects at its side 55 edges somewhat beyond the side slabs *m*. The strips *o* and pieces *q* may be secured together by screws *t* and the planking may be secured to the strips by nails or screws *u*, for example. The slab *s* may be constructed intact with the structure formed by the

parts *o, q, r*, as by securing it thereto by nails, screws or the like (not shown); or it may be left detached, so that said structure can be fitted to the body part of the overbox first and then the slab applied afterward. In any event, the tops of the end frames *a* and the strips *f* have screw holes *v*, and to register with these holes slab *s* has holes *w*, and through these holes *w* and into the holes *v* screws *x* are adapted to be entered to fasten down the slab after the casket has been deposited therein. (The joints between the slab *s* and the opposed surfaces formed by the side and end slabs *m* and the tops of the frames *a* and strips *f* 70 may be sealed with cement or other plastic material—not shown). In order to insure precise registry of the holes *w* with the screw-holes *v*, I provide on the hangers *p* downwardly projecting tapered studs *y*, 75 which when they are entered into corresponding holes *z* in applying the lid shift the strips *f* inward or outward, in case they become slightly sprung or flexed, sufficiently to establish such registry. In view of the foregoing description it will be seen that the construction of the cover or lid and the manner of connecting it with the top portion of the body of the overbox not only make the cover or lid in itself strong, 80 though light, and adapted to sustain a considerable load, but appreciably reinforce the entire overbox.

Having thus fully described my invention, what I claim as new and desire to secure by Letters Patent is:—

1. In a burial overbox, the combination of metallic substantially rectangular end frames composed of angle-iron strips, said frames being arranged with their inside angles inward, means to brace and connect said end frames together including four parallel angle strips connecting the corresponding corners of the end frames and having their inside angles receiving said corners, 105 rectangular bottom, side and end slabs of lithoidal material secured to the end frames and said strips along the respective edges of said slabs, and a cover including a rectangular slab of lithoidal material secured to 110 the end frames and two of said strips along its several edges.

2. In a burial overbox, the combination of metallic substantially rectangular end frames each consisting of an angle strip bent 115 at intervals at right angles to one wall thereof and having the other wall thereof at each point of bending mitered out, said frames being arranged with their inside angles inward, means to brace and connect said end frames together including four parallel angle strips connecting the corresponding corners of the end frames and having their inside angles receiving said corners, rectangular bottom, side and end slabs of lithoidal 120

125

130

material secured to the end frames and said strips along the respective edges of said slabs, and a cover including a rectangular slab of lithoidal material secured to the end 5 frames and two of said strips along its several edges.

3. In a burial overbox, the combination, with a rectangular metal frame, of a bottom slab, two end slabs, and two side slabs of 10 lithoidal material secured to five sides of the frame and forming therewith the body portion of the overbox open at the top, and a cover for the overbox including metal trans- 15 verse strips having their ends formed as up- turned hangers seated on the tops of opposite sides of the frame, a slab of lithoidal material secured along its several edges to the frame, supporting means for the latter slab including a batten arranged on and ex- 20 tending longitudinally of each strip between the hangers thereof and extending substantially from one side slab to the other and planking arranged on the battens, said latter slab and planking being in face to face contact with each other.

15 4. In a burial overbox, the combination, with a rectangular metal frame, of a bottom slab, two end slabs, and two side slabs of lithoidal material secured to five sides of the 25 frame and forming therewith the body portion of the overbox open at the top, and a cover structure for the overbox, the cover structure having along its several edges holes to receive securing devices and also 30

35 cover for the overbox including metal trans- 30 verse strips having their ends formed as up- turned hangers seated on the tops of opposite sides of the frame, a slab of lithoidal material secured along its several edges to the frame, supporting means for the latter slab including a batten arranged on and ex- 35 tending longitudinally of each strip between the hangers thereof and extending substantially from one side slab to the other and planking arranged on the battens, said latter slab and planking being in face to 40 face contact with each other.

5. In a burial overbox, the combination, with a rectangular metal frame, of a bottom slab, two end slabs, and two side slabs of lithoidal material secured to five sides of the 45 frame and forming therewith the body portion of the overbox open at the top, and a cover structure for the overbox, the cover structure having along its several edges holes to receive securing devices and also 50

downward tapering studs, and the frame having at its top holes to receive the securing devices and other holes to receive the studs.

In testimony whereof I affix my signature. 55
JOHN GERY.
